FUEL FEEDER

Weston M. Fulton, Knoxville, Tenn., assignor to
 W. J. Savage Company, Inc., Knoxville, Tenn.,
 a corporation of Tennessee

Original application October 4, 1940, Serial No.
 359,794, now Patent No. 2,361,836, dated October
 31, 1944. Divided and this application June 17,
 1941, Serial No. 398,501

3 Claims. (Cl. 198—128)

This invention relates to an improvement in fuel feeders of the type used in connection with stokers for supplying coal or other solid fuel to the fuel beds of heaters. This application is a division of my prior application on Stokers, Ser. No. 359,794, filed October 4, 1940, now Patent No. 2,361,836, granted October 31, 1944.

Experience has demonstrated the fact that where fuel is fed directly on top of the fuel bed in a heater, it is difficult to obtain a fuel bed having a fairly level top surface. For instance, some stokers cause the fuel to pile up in the center of the fuel bed, thus making the bed much thicker in its central portion than it is around the periphery thereof.

Furthermore, the largest and most immediate demand for stokers of this type, is for use in heating plants that have employed hand firing heretofore, but a stoker to supply this demand, must be adaptable to a wide variety of heaters. In many heaters, the fire-bowl is located at a considerable distance back of the fire door which makes it necessary to convey the fuel a substantial distance in the heater after it has been delivered at the fire door.

Various mechanical devices have been proposed heretofore for accomplishing this purpose, but they have possessed objectionable characteristics. For instance, high pressure steam is used to blow the fuel from the fire door entrance into the fire box. To be fairly successful, this method would require a source of high pressure steam, which is seldom if ever available in house heating plants, because, where steam is used as the heating medium, very low pressure of one or two pounds is used, and where hot water or hot air is used, steam is not available at all.

In a stoker in which a rotating wheel having radially extending blades is used to throw the fuel into the fire box, but the wheel is of the "undershot" type, this requires the fuel to pass below the axis of rotation and this results in clogging the feeder due to the downward forcing of the fuel against the bottom of the feed trough thus allowing lumps to be caught between the descending blades of the wheel and the feed trough. If the rotation of the wheel be reversed so as to feed the fuel in an "overshot" manner, then some of the fuel is wasted, gathers in the bottom of the fuel trough, and finally causes clogging.

The object of this invention is to improve the construction of the stoker of the class described, in which the objections heretofore encountered in connection with ballistic fuel feeders are com-

pletely obviated permitting the practical utilization of this type of stoker, and yet in a construction which can be manufactured economically and used practically, and in which provision is made for securing an even distribution of the fuel over the fuel bed during feeding thereof into the heater.

A further object of the invention is to improve the construction of ballistic fuel feeders to provide for practical operation thereof in connection with stoking mechanism, and to prevent the clogging of such a feeder during the feeding operation, as well as to return to the source of supply any fuel not accurately fed to the combustion chamber of the heater.

These objects are accomplished in a practical structure as hereinafter described, a preferred embodiment of which is illustrated in the accompanying drawing, which is a partial vertical sectional view thereof shown applied to a conventional form of heater with parts in elevation.

The invention is shown in connection with a heater designated generally by the numeral 1, which may be of any conventional form to which it may be desired to feed fuel by a stoker, such as a house heating furnace or the boiler or other type as desired. The furnace 1 is shown as having the usual combustion chamber 2 therein adapted to contain a fuel bed F to which fuel may be fed as desired through the usual opening 3 normally controlled by a fire door.

When the invention is applied to a heater of the type already in use, the usual fire door is removed from over the opening 3, and is replaced by a frame 4, which is secured to the heater by bolts 5. An opening 7 in the frame 4 is adapted to receive the fuel feeding mechanism, as hereinafter described.

A fuel hopper 11 is arranged in front of the heater 1, of a size to contain a predetermined quantity of fuel to supply the heater for a substantial period of time. The hopper 11 has a back wall 12 behind which is provided an enlarged compartment 13 formed between a bottom wall 14 and a top wall 15. A tubular extension 16 projects from the compartment 13 through the opening 7 substantially to the combustion chamber 2 of the heater. The tubular extension 16 is secured to the heater by means of the bolts 5.

This tubular extension 16 has partitions 17 and 18 dividing the same into three superposed passageways 19, 20 and 21, respectively, the purpose of which will be hereinafter described.

The hopper 11 has an upward extension 22 adjacent the back thereof within which are

mounted interfitting twin screws 23, constituting a conveyor and constructed substantially as set forth in my prior patent on Feeder, No. 2,173,414, granted September 19, 1939. A baffle plate 24 extends downward in the hopper 11 in front of the twin-screw conveyor to keep the major portion of the body of fuel in the hopper, away from interference with the rotation of the conveyor screws, while allowing the fuel to be fed thereto adjacent the bottom thereof. A retention plate 25 extends vertically along the back of the conveyor 23, and is spaced from the back wall 12 of the hopper a sufficient distance to allow fuel to fall back between the retention plate and the back wall, through an opening 26 in the latter, if it should fail to be injected into the fire chamber of the heater as hereinafter described.

The upper ends of the twin screws 23 have intermeshing gears 27 fixed thereon and intermeshing with each other. A drive gear 29 meshes with the gears 27 and is fixed on the slow speed shaft of a speed reducer designated generally by the numeral 30, this being of any well-known construction. The speed reducer 30 has a high speed drive shaft 31 which is driven by a pulley 32 thereon, connected with a belt 33 that extends to a pulley mounted on the armature shaft of an electric motor 35. The electric motor 35 and speed reducer 30 are mounted on a bracket 36 secured upon the upper end of the hopper extension 22 and upon the top 15 of the compartment 13, which bracket 36 also extends over the gears 27 and 29.

Journalized in opposite sides of compartment 13 is a shaft 37 having a pulley 38 thereon connected by a belt 39 with a pulley 40 mounted on the high speed shaft 31 of the speed reducer 30, to impart a high speed rotation to the shaft 37 upon the operation of the electric motor 35.

Mounted on the shaft 37 is a fuel-injecting wheel designated generally by the numeral 41. The wheel 41 is constructed with an annular drum 42 with outwardly projecting annular flanges 43 thereon and having blades 44 extending transversely between the flanges 43 radially of the drum and cooperating with the flanges to form buckets or pockets therebetween.

The fuel-injecting wheel 41 is mounted in the compartment 13 beneath the lower end of a chute 45, which chute extends substantially to a point approximately directly over the center of the wheel 41, so as to deliver fuel to the top thereof, the upper end of the chute 45 being connected with the retention plate 25 at the upper end of the screw conveyor 23 to receive fuel therefrom. The fuel-injecting wheel 41 is arranged adjacent the forward end of the passageway 19, but spaced therefrom.

Thus, when the fuel is elevated from the hopper 11 by the twin screw conveyor 23 into the upper end of the chute 45, it is discharged directly onto the rotating wheel 41. The fuel drops into the pockets or buckets formed in the periphery of the wheel between the blades 44, and due to the high speed of rotation of the wheel, these blades exert a strong ballistic force on the fuel to throw it tangentially from the wheel 41 through the passageway 19 into the combustion chamber 2 of the heater. As will be evident, by imparting to the wheel 41, the proper speed of rotation and by adjusting the chute 45 to discharge the fuel onto the wheel at the proper point, the fuel can be thrown directly through the compartment 19 into the combustion chamber of the heater.

Heretofore, the ballistic type of feeders pro-

posed have been objectionable because if fuel particles should fall onto the upper edges of the rotating blades, these particles would not have as much force imparted to them as if they had fallen in front of a blade so as to receive the full force thereof. This would allow the particles to drop around the wheel and finally fill up the space between the wheel and its enclosing housing, thus resulting in a clogging of the wheel which interferes with its proper rotation.

However, I have overcome this objection by placing the forward edge of the wheel 41 sufficiently far from the open end of the passageway 19, as well as from the inclined wall 14 of the compartment 13, to provide a liberal space therebetween so that all waste fuel which would not have sufficient force imparted thereto by the rotating blades, to inject the same through the passageway 19 into the combustion chamber of the heater, would have freedom for return movement along the inclined wall 14, thence through the opening 26 into the hopper.

The waste fuel thus discharged into the hopper 11 is allowed to fall between the back wall of the hopper and the retention plate 25 to a point where it is picked up again by the conveyor 23 along with the other fuel thus elevated during the feeding operation. As pointed out above, the baffle 24 prevents the fuel from rising up around the bottom of the conveyor 23 sufficiently high so that it would prevent the free discharge of the returned fuel through the opening 26 into the hopper. Furthermore, the action of the twin screws is such as to keep the fuel level very low at the opening 26, so as to accommodate this return fuel.

Located in passageway 20 is mechanism for causing the fuel to be deflected uniformly over the fuel bed F, as it is injected through the passageway 19 into the combustion chamber. This mechanism is disclosed more in detail and claimed, in my co-pending application on Stokers, Ser. No. 359,794, filed October 4, 1940, now Patent No. 2,361,836. It includes an arm 46 pivotally supported on a bracket 48 and extending lengthwise through the passageway 20 into the combustion chamber 2 of the heater. The forward end of the arm 46 carries a downwardly extending baffle structure 52 arranged substantially in the path of fuel injected through the passageway 19 into the combustion chamber 2, to deflect the fuel onto the fuel bed.

Provision is made also for controlling the thickness of the fuel bed F in the combustion chamber 2 of the heater and to level the fuel thereover, by mechanism set forth more in detail and claimed in my application on fuel feeding mechanism. This involves the use of a rod 76 extending lengthwise through the passageway 21 into the combustion chamber 2 of the heater, and carrying a bar 81 on the free end thereof in position to contact the surface of the fuel in the heater and to ride thereon.

The rod 76 has its opposite end supported at 32 for universal movement, and intermediate its ends, the rod 76 passes through a guiding device designated generally 89 which forms a pivotal support for the rod 76 and actuates a control switch 96 adapted to control the operation of the electric motor 35 in response to vertical movement of the rod 76. An oscillating movement is imparted to the rod 76 by its pivotal connection 82 through linkage designated generally at 86 operated by the electric motor 35 through connection thereof with one of the gears 27.

I claim:

1. In a fuel feeder, the combination of a conduit, a rotary injector member having radially arranged projecting means on the periphery thereof, means mounting said member for turning movement with the periphery thereof spaced from the adjacent end of the conduit for injecting solid fuel into the conduit while allowing some material to fall through the space between the injector member and the conduit, said conduit having the lower edge thereof below the top of the injector member and above the center of said injector member, a fuel receptacle having fuel feeding means arranged for feeding fuel therefrom to the injector member, said receptacle having an opening in a side thereof, and an inclined wall extending downwardly from the conduit beneath the space between the injector member and the end of the conduit to the opening for directing into said opening fuel falling through said space, said injector member being unenclosed on the side thereof toward the adjacent end of the conduit throughout at least half of the circumference thereof whereby the fuel not injected into the conduit will fall onto the inclined wall and be directed thereby into the receptacle.

2. In a fuel feeder, the combination of a conduit, a rotary injector member, means mounting said member for turning movement with the periphery thereof spaced from the adjacent end of the conduit for injecting solid fuel into the conduit while allowing some material to fall through the space between the injector member and the conduit, a fuel receptacle having fuel feeding means arranged for feeding fuel therefrom to the injector member, said receptacle having an opening in a side thereof, an inclined wall extending downwardly from the conduit beneath the space between the injector member and the end of the conduit to the opening for directing into said opening fuel falling through said space, the fuel

feeding means extending into the receptacle adjacent said opening, and a partition extending downwardly in the receptacle between the opening and the fuel feeding means and spaced from the side of the receptacle having the opening for directing the returned fuel to the bottom of the receptacle.

3. In a fuel feeder having a chamber, an elongated conduit extending from said chamber to a point externally thereof, a rotary injector constructed with peripheral pockets, means for operating said injector at high speed in an over-shot direction to inject material through the conduit into the chamber, and means mounting said injector adjacent the outer end of the conduit and in fixed relation spaced therefrom for flow of the material through the conduit, said conduit having the lower edge thereof below the top of the injector member and above the center of said injector member, a fuel receptacle having fuel feeding means arranged for feeding fuel therefrom to the rotary injector, said receptacle having an opening in a side thereof, and an inclined wall extending downwardly from the conduit beneath the space between the injector and the end of the conduit to the opening for directing into said opening fuel falling through the space, said injector member being unenclosed and exposed at its periphery throughout at least half of the circumference thereof toward the adjacent end of the conduit and open to the space between said member and conduit, said space being unobstructed throughout the lower circumference of the injector member between a vertical plane through the axis of said member and the end of the conduit down to the inclined wall, whereby the fuel not injected into the conduit will fall onto the inclined wall and be directed into the receptacle.
